CORDLESS ELECTRIC GRASS SHEAR

Donald J. Behnk, Allison Park, and James E. Edgell,
Bradford Woods, Pa., assignors to Disston, Inc., Pitts-
burgh, Pa.

Filed July 12, 1974, Ser. No. 488,174

Term of patent 14 years

Int. Cl. D8—01

U.S. Cl. D8—8

FIG. 1

FIG. 2

FIG. 3

FIG. 4

FIG. 5

FIG. 6

FIG. 1 is a perspective view of a cordless electric grass shear embodying our new design.

FIG. 2 is a front elevation view thereof.

FIG. 3 is a rear elevation view thereof.

FIG. 4 is a top plan view thereof.

FIG. 5 is a bottom plan view thereof.

FIG. 6 is a side elevation view thereof which is a mirror image of its laterally opposite side.

We claim:

The ornamental design for a cordless electric grass shear, substantially as shown.
